(57) **CLAIM**

The ornamental design for a portable electric vacuum suction cup as shown and described.

DESCRIPTION

FIG. 1 is a perspective view of a portable electric vacuum suction cup showing our new design;

FIG. 2 is another perspective view of the portable electric vacuum suction cup, shown in an alternate configuration;

FIG. 3 is a top view of FIG. 1;

FIG. 4 is a right side view thereof;

FIG. 5 is a front view thereof;

FIG. 6 is a left side view thereof;

FIG. 7 is a rear view thereof; and,

FIG. 8 is a bottom view thereof.

The broken lines in the figures are for the purpose of illustrating portions of the portable electric vacuum suction cup which form no part of the claimed design.
